UNITED STATES PATENT OFFICE.

CHARLES M. B. SCHWARTZ, OF BROOKLYN, NEW YORK.

TRANSFER-TICKET.

961,028.

Specification of Letters Patent. Patented June 7, 1910.

Application filed April 4, 1908. Serial No. 425,188.

To all whom it may concern:

Be it known that I, CHARLES M. B. SCHWARTZ, a citizen of the United States, residing at Brooklyn, in the county of Kings and State of New York, have invented new and useful Improvements in Transfer-Tickets, of which the following is a specification.

This invention relates to improvements in transfer tickets particularly for use in connection with street railways and more particularly in what are termed time limit transfer tickets for use by street railways, traction companies etc. for transferring passengers from a car of one line to a car of another line at a given transfer point and the object thereof is to provide a transfer ticket to enable the railroad company to make the transfer as quickly as possible and keep absolute check on the conductors and passengers and by this check to be able to ascertain without question whether the transfers have been correctly issued by the conductors and whether used by the passengers according to conditions under which they are issued or whether these conditions have been abused.

A further object of the invention is to provide a transfer ticket in a manner as herein-after set forth whereby it can be utilized for transferring a passenger at the initial point of transfer as well as one or more subsequent points of transfer and by such arrangement provides what may be termed a duplex transfer ticket so that a single ticket can be utilized to transfer a passenger from one to two or more lines.

A further object of the invention is to provide a transfer ticket for use in connection with street railways or for other purposes wherein it is thought applicable with means in a manner as hereinafter set forth to prevent the use of a ticket issued for ante-meridian being used post-meridian.

A further object of the invention is to provide a transfer ticket for use in connection with street railways or for other purposes wherein it is found applicable with means in a manner as hereinafter set forth which when issued for use ante-meridian will be so mutilated as to prevent the ante-meridian ticket being used post-meridian.

Further objects of the invention are to provide a transfer ticket which shall be comparatively simple in its construction, conveniently issued by the conductor, affording its utilization for transfer of a passenger

from one or more lines of the railway company, and inexpensive to manufacture.

With the foregoing and other objects in view, the invention consists of the novel arrangement of a transfer ticket hereinafter more specifically described and illustrated in the accompanying drawings, wherein is shown the preferred embodiment of the invention, but it is to be understood that changes, variations and modifications can be resorted to which come within the scope of the claims hereunto appended.

In describing the invention in detail, reference is had to the accompanying drawings, wherein:—

Figure 1 is a front elevation of a transfer ticket in accordance with this invention, and Fig. 2 is a rear elevation.

Referring to the drawings in detail 1 denotes the body portion of the ticket having at each end a coupon as at 2, 3. The front face of the body portion 1 is provided with means as at 4 to constitute an hour time limit. Said means consists of the numbers 1 to 12 and said body portion 1 is furthermore provided with means as at 5, 6 constituting a duplex fraction of an hour time limit. By way of example the fractions are indicated as 10, 20, 40. Each duplex fraction of an hour time limit is arranged at one end of the hour time limit. The fraction of the hour time limit 5 surrounds a pair of cardinal points 7, 8, as shown the letters "N" and "S" indicating north and south. The fraction of the hour time limit 6 surrounds a pair of cardinal points 9, 10, as shown the letters "E" and "W" indicating east and west. The outer face of the body portion 1 is also provided with means as at 11 to indicate the day upon which the transfer is issued and furthermore provided with the conductor's number, as at 12, the name of the line as at 13, an inscription as at 14 designating that the hour punched in the time limit 4 is ante-meridian and further has an identifying number as at 15. The cardinal point 7 as well as the fraction of the hour indications which surround said cardinal point are upon a red background, the cardinal point 8 upon a green background, the cardinal point 9 has a background similar to that of the body portion and the cardinal point 10 upon a yellow background.

The outer face of the coupon 2 is provided with an identifying number 16 which corre-

sponds to the number 15 and is furthermore provided with means to constitute an hour time limit as at 17, said means consisting of the numbers 1 to 12, said numbers being 5 upon a red background, the coupon 2 being what is termed the North coupon. Above the time limit 17 is a conventional means as at 18 to indicate ante-meridian, as shown the letters A. M. and below said time limit 10 17 is an inscription as at 19 to indicate to the passenger that the hour punched is ante-meridian and further indicates to the passenger in what direction the coupon is to be used. Below the inscription 19 is means to 15 indicate a cardinal point as at 20, said means consisting of the word "North" arranged upon a red background.

The outer face of the coupon 3 is provided with an identifying number as at 21 which 20 corresponds to the number 15 and is furthermore provided with means to constitute an hour time limit as at 22, said means consisting of the numbers 1 to 12, said numbers being upon a green background, the coupon 3 25 being what is termed the "south" coupon. Above the time limit 22 is a conventional means as at 23 to indicate ante-meridian, as shown the letters A. M., and below said time limit 22 is an inscription as at 24 to indicate 30 to the passenger that the hour punched is ante-meridian and further indicates to the passenger in what direction the coupon is to be used. Below the inscription 24 is means to 35 indicate a cardinal point as at 25, said means consisting of the word "South" arranged upon a green background.

The rear face of the body portion 1 is provided with means to constitute an hour time limit as at 26, said means consisting of the 40 figures 1 to 12 and so disposed with respect to the time limit 4 that when it is punched the time limit 4 will not be mutilated and the same arrangement is had with respect to the mutilation of the time limit 4 as the 45 time limit 26 will not be mutilated. The rear face of the body portion 1 is furthermore provided with duplicate fraction of the hour time limits as at 27, 28, one arranged at each end of the time limit 26. The fractions 50 of the hour are indicated by way of example as 10, 20, 40. The duplex time limit 27 surrounds means to indicate a pair of cardinal points as at 29, 30, said means being the letters E and W which indicate east and 55 west. The fraction of the hour time limit 28 surrounds means to indicate a pair of cardinal points as at 31, 32, said means consisting of the letters N and S which indicate north and south. Above the time limits 60 26, 27 and 28 is an inscription as at 33 which constitutes a warning to the passenger. Above the inscription 33 is means to indicate the name of the line of the railway as at 34. The rear face of the body portion 1 is furthermore provided with the con-

ductor's number as at 35 and an inscription as at 36 to indicate that the hour punched is post-meridian and further indicates in which direction the body portion is to be used.

The rear face of the coupon 2 is provided with means to constitute an hour time limit as at 37, said means consisting of figures 1 to 12. Above the time limit 37 is an inscription as at 38 to indicate that the hour punched in the time limit 37 is post-meridian and said inscription further indicates in which direction the passenger is to travel. Above the inscription 38 is means to indicate one of the cardinal points as at 39, said means 80 consisting of the word "North." Above the word "North" is arranged the conductor's number as at 40 and a conventional means to indicate post-meridian as at 41. By way of example the said means are the letters 85 P. M.

The rear face of the coupon 3 is provided with means to constitute an hour time limit as at 42, said means consisting of the figures 1 to 12. Above the time limit 42 is an inscription as at 43 to indicate that the hour punched in the time limit 42 is post-meridian and said inscription further indicates in which direction the passenger is to travel. Above the inscription 43, as at 44, 95 is means to indicate one of the cardinal points, said means consisting of the word "South." Above the word "South" is arranged the conductor's number as at 45 and a conventional means to indicate post-meridian as at 46. By way of example the said means are the letters P. M.

The time limit 37 is so disposed with respect to the time limit 17 that when one is punched the other will not be mutilated and 105 the same arrangement is had in connection with the time limit 42 with respect to the time limit 17, and further in connection with the time limits 27, 28, with respect to the 110 time limits 5 and 6.

In addition to the disposition of the hourly time limit indicating means on the obverse and reverse faces of each coupon, cardinal point indicating means or the words "North" and "South" are in like manner 115 in reverse position on the obverse and reverse faces of each coupon, and by thus disposing the hourly time limit and cardinal point indicating means confusion in mutilating either means to indicate north usage in one instance and south usage in another instance will not ensue with material advantages in avoiding mistakes on the part of the conductor and preventing the passenger receiving the transfer from making a 120 wrong use of the same. Each coupon is also confined for use in direction of travel solely to one point of the compass on each face and the individual coupons as shown bear cardinal point indicating means differing 125 130

in kind on their obverse faces as well as on their reverse faces.

The front face of the body portion 1 is provided with conventional means as at 47 5 to indicate ante-meridian and the rear face of the body portion is provided with conventional means as at 48 to indicate post-meridian. The conventional means indicating ante-meridian are the letters A. M. 10 and that indicating post-meridian are the letters P. M.

The manner in which the ticket is used is as follows:—By way of example, however, it will be stated that the transfer is provided 15 with two coupons, but this number can be increased or diminished if desired. It will be assumed that a passenger traveling north at 9.40 a. m. after paying fare will ask for a transfer ticket. The passenger need not 20 say to what line he desires to be transferred. On the application by the passenger for a transfer ticket the conductor will punch the figure 10 of the coupon 2, the cardinal point "North" as well as the figure 10 in 25 the body portion of the ticket upon the outer face of same in time limit, also identifying number 2 in South coupon, to indicate to the auditor of any company that this coupon 30 cannot be claimed by conductors as a cash fare in their favor. When the car reaches the transfer point at which the passenger is to transfer, the passenger leaves the car and boards the car on the line to which he 35 is transferred, the conductor on this latter line takes up the ticket from the passenger and sees at a glance that the "South" coupon is not mutilated in the time limit and that the rest of the ticket is properly punched. The conductor detaches the 40 "South" coupon and registers the same as a fare received. It will be assumed that the car is traveling "east" and the conductor returning the ticket back to the passenger punches the fraction of the hour "10" 45 which is arranged above the cardinal point E, and then hands the ticket which now consists of the body portion 1 and coupon 2 back to the passenger. The transfer ticket 50 having been marked "North" and "East" with time limit, the passenger cannot use the ticket to travel back in the direction which he came on the line by which the ticket was issued. Arriving at the second point of 55 transfer, say for instance, the passenger desires to transfer to a car going north again, the conductor upon the car when the ticket is handed to him notes that the ticket has been punched at the means to indicate the cardinal points "east" and "north" and also 60 notices that the coupon 2 is attached to the body of the ticket. The conductor detaches the coupon 2 and registers it as a fare, but before returning the body portion to the passenger he punches the fractional portion 65 of the hour 20 or 40 as the case may be at

the side of the means to indicate the cardinal point "North" on the body of the ticket. Arriving at the third point of transfer, the passenger may now travel in a western direction if he chooses to or he may be also 70 permitted to go in almost any direction indicated by any point of the compass over some other line of the company if it is provided for by the rules of the company. In this connection it will be stated that at the 75 third point of transfer the body portion of the ticket is taken up by the conductor for passage.

It is of importance that the points of the compass, especially on coupons, be printed in 80 colors as presented to avoid mistakes on the part of the conductor in either punching tickets or detaching coupons. It does not matter whether directions and time limits combined in the body portion when punched 85 show an exact space on either face of the ticket as the ticket is valid only having the hours from 1 to 12 punched after the A. M. is passed. The only thing the conductor does is he turns over as many tickets as he 90 thinks he will use and punches in the same manner as on the front face or ante-meridian.

The main line in some cities may run 95 from east to west, then as a matter of course the coupons have to be designated "North" and "South" for branch or cross town lines connecting the main lines.

Conductors receiving a complete transfer ticket with all coupons attached and passengers declining to re-transfer, the conductor cannot turn in such a ticket to the company and claim credit for three fares in his favor instead of only one. The conductor after 100 finishing each trip has to place the received tickets into a sealed envelop with the time marked thereon. The auditor of the company the following day looking over the time marked on each envelop and the number of trips will see by the serial number 105 which is the same on each part of the ticket with time limit and directions marked as well as the conductor's number on each of the three parts of the ticket that this conductor has made an incorrect report and will 110 be called upon to make good two cash fares rightly belonging to the company. A conductor not having the same number corresponding to the ticket cannot issue tickets 115 belonging to some one else, as such action on his part will be readily discovered.

What I claim is:—

1. A transfer ticket comprising a body portion and a coupon, said body portion and coupon having their obverse and reverse 125 faces provided with hourly time limit indicating means and conventional means to indicate a cardinal point, the two cardinal points indicated one upon each of the two faces of the coupon being identical, the 130

hourly time limit means and cardinal point indicating means being out of registration on the two faces of the coupon, one of said cardinal point indicating means on the body 5 being similar to the said means on the coupon, and another cardinal point indicating means on the body differing from the cardinal point indicating means on the coupon, the body portion of the ticket also 10 having ante-meridian and post-meridian indicating means thereon, and means on each face of the transfer indicating how the latter must be punched in order to be good.

2. A transfer ticket comprising a body 15 portion and two separable coupons, one coupon being connected to each end thereof, said body portion and coupons each bearing on obverse and reverse sides thereof hourly time limit means and conventional indications to constitute an ante-meridian 20 and a post-meridian transfer ticket respectively, the said hourly time limit means being in different positions on the two faces of the body portion and coupons.

3. A transfer ticket comprising a body 25 portion and two coupons, the coupons being individually and separably connected to opposite ends of the body portion, said body portion and coupons each bearing on obverse and reverse faces hourly time limit means and conventional indications to constitute ante-meridian and post-meridian transfer means respectively, the obverse and reverse faces of the coupons and of the body 30 portion of the ticket also having cardinal point indicating means on said faces of each, the cardinal point indicating means of one coupon on one face thereof differing from that on the same face of the other coupon 35 and the cardinal point indicating means on each face of the body portion of the ticket being the same as the two differing cardinal 40

point indicating means on the corresponding faces of the coupons, the body portion of the ticket also carrying cardinal point indicating means differing from the cardinal point indicating means on the coupons, the cardinal point indications and the hourly time limit means on the two faces of each coupon and on the body being in different 45 50 positions.

4. A transfer ticket comprising a body portion and two coupons, the latter being separably connected one to each of the opposite ends of the body portion, said body portion and coupons each bearing on obverse and reverse sides thereof hourly time limit means and conventional indications to constitute ante-meridian and post-meridian transfer means, the obverse and reverse faces of the 55 coupons and of the body portion of the ticket also having cardinal point indicating means on the said faces of each, the said hourly time indicating limit means and the cardinal point indicating means being in 60 65 different positions on the two faces of each coupon, and the body portion of the ticket having the ante-meridian and post-meridian indicating means in different positions on the two faces thereof and the cardinal point indicating means in the same position on the two faces so that in punching anyone of the cardinal point indicating means on either 70 75 face of the body portion an identical cardinal point indicating means will be likewise punched on the opposite face.

In testimony whereof I have hereunto set my hand in presence of two subscribing witnesses.

CHARLES M. B. SCHWARTZ.
